ERASING ATTACHMENT FOR TYPEWRITERS

Charles R. Bennett, East Cleveland, Ohio

Application March 27, 1944, Serial No. 528,201

6 Claims. (Cl. 197—181)

This invention relates to erasing attachments for typewriters and more particularly relates to an erasing attachment which is key operated.

One of the objects of the invention is to provide a simple and effective erasing device which may readily be attached to typewriters of various makes and which is operated in much the same manner as the type arms of the machine, that is, by means of a key.

Another object of the invention is to construct a key operated erasing device for typewriters which is provided with an erasing head and a relatively movable erasing means operable upon impact of the head with the platen and the sheet of paper carried thereon to cause the erasing means to movably engage the surface of the paper under pressure sufficient to remove any undesirable characters from the surface of the paper engaged by the eraser.

Another object of the invention is to provide a typewriter erasing attachment with means whereby the device may be so mounted that upon depression of the actuating key, the erasing element will move into proper alignment or position to strike the platen upon the character to be erased.

Other objects and advantages of my invention will become more apparent from the following description of an embodiment thereof reference being made to the accompanying drawing in which like reference characters are employed to designate like parts throughout the same.

In the drawing:

Figure 1 is a plan view of my invention shown applied to a typewriter, the latter being shown only in outline for purposes of illustration;

Figure 2 is an enlarged plan view of a device embodying my invention and shows the erasing elements or scrapers in erasing engagement with the paper on the platen when the eraser key is depressed;

Figure 3 is a front view of the eraser head looking to the right at Figure 2; and,

Figure 4 is a view similar to that of Figure 2 but illustrates the relation of the parts when the head is withdrawn to the broken line position in Figure 1.

Referring now more particularly to the drawing in which I have illustrated one embodiment of the invention, a typewriter is indicated generally at 1 and is provided with the usual platen 2 for receiving a sheet of paper in the usual manner on which characters are to be typed.

In carrying out my invention I have provided an arm 3 pivoted at 4 to the frame of the type-

writer to swing in a substantially horizontal plane toward and away from the platen 2. The rear end of the arm is formed with a projection 5 apertured at 6 to receive the looped end of a link 7 which is connected at its other end 8 with a rocking lever 9 pivotally mounted on a boss 10 formed on the frame 1. A coiled spring 11 connects the typewriter frame with the mid portion of the link at 12.

A key 13 on the key arm 14 hinged at 15 is also connected with the rocking lever 9 by means of a link 16 so that when the key is depressed, motion will be transmitted through the linkage 7 and 16 and the rocking lever 9 to swing the eraser arm 3 about its pivot 4 to the full line position shown in Figure 1, that is, to impact the eraser element carried, by the eraser head 17, with the platen 2.

Referring now more particularly to Figures 2, 3 and 4, I will describe the construction and operation of the eraser device carried by the arm 3. A head 17 is formed on the outer end of the arm and comprises a pair of parallel side walls 18 and 19 spaced apart and grooved internally at 20 to provide a guide way for the plunger 21 which is adapted to slide along the guide way in either direction. The plunger is normally urged upwardly as in Figure 4 by the compression spring 22 which may be interposed between the bottom wall 23 of the guide way and the bottom surface of the plunger 21 as shown in Figure 2. The upper portion of the plunger, which is substantially U shape, is formed with a pair of guards or stops 24, the outer end surfaces of which engage the paper on the platen 2 when the key 13 is depressed. A transverse bar 25 is spaced below the guards 24 and is provided as a horizontal support for the eraser belt 26 over which the latter passes or slides as the device is operated.

Adjustably secured to one outer side of the head 17 is a rack 27 along which the pinion 28 carried by the eraser wheel 29 travels, the wheel 29 and the pinion rotating together as a unit. It will be seen that the eraser wheel 29 rotates within the U shaped plunger, the wheel shaft 30 being rotatably mounted in the arms of the plunger and extending outwardly thereof on both sides and through the elongated slots 31 and 32 formed in the parallel sides of the head 17. These slots serve to further guide the movement of the plunger in the head and also act to limit the movement thereof in both directions. One end of the wheel shaft 30 carries the pinion on the outer side of the adjacent head side wall 18.

so that the teeth of the pinion may engage the teeth of the rack as shown in Figure 2.

The erasing element consists of a belt 26 overlying and anchored at one point to the periphery of the wheel 29, the belt also being threaded over the belt bar 25 as previously explained. A plurality of abrasive, scraping or cutting members 31 is carried by the belt and are so arranged that the effective abrasive, scraping or cutting areas or surfaces thereof pass between the guards 24 and sufficiently beyond the outer confines thereof to effectively engage the paper on the platen 2 for the purposes explained when the key 13 is depressed as shown in Figures 2 and 4.

Since the spring 22 normally tends to project the plunger upwardly in the head, the erasing elements 31 will be positioned to the right of the plunger as in Figure 4 ready to be driven across and in contact with the paper area to be erased upon a downward movement of the plunger due to impact of the guard with the platen. As the plunger is forced back into the head as in Figure 2 against the compression of the spring 22, the pinion 28 will travel along the rack 27 and such movement will rotate the eraser wheel 29 in a counter-clockwise direction, thus bringing the erasing elements across and between the guides 24 and at the same time in effective erasing contact with that portion of the paper which lies within the type space 32 and which contains a character to be erased.

While I have shown the erasing elements 31 as comprising blades for scraping the paper surface during the erasing operation, it is to be understood that in place of the blades 31, abrasive or rubbing members may be employed with equally effective results.

As the head is retracted or moved away from the platen, partly by the force of the spring 22 and also with the aid of spring 11, the plunger 21 and the erasing wheel 29 carried thereby will be projected upwardly and outwardly of the head as indicated in Figure 4 in position for the next impact blow against the platen. Of course, as the head 17 and the arm 3 move away from the platen toward the broken line position in Figure 1, the key 13 will return to its former upper position, such motion of the arm 3 being transmitted through the links 7 and 16 and the rocking lever 10 to the key bar 14.

From the foregoing description and the drawing, it will be seen that by my invention I have provided an eraser attachment for typewriters which is of extremely simple construction and positive in operation and that the same is as easy to operate as any other key on the keyboard, since by simply depressing the key 13 sharply the arm 3 is swung toward the platen to engage the guards 24 with the platen in the type space 33 under a sufficiently sharp impact blow to cause the extended plunger 21 to be telescoped rearwardly in the head 17, such movement of the plunger rotating the erasing wheel 29 in a counter-clockwise direction to cause the erasing elements 31 to engage the paper in the type space with sufficient scraping, abrasive or cutting force to remove the outer surface of that portion of the paper together with any character which it is desired to erase.

Various changes may be made in the details of construction and arrangement of parts without departing from the spirit of the invention or the scope of the following claims.

I claim:

1. In a key operated erasing attachment for a typewriter having a platen, an eraser element, a swinging carrier for the eraser, said eraser element being movable in the carrier in a direction substantially parallel to the axis of the platen in response to an impact blow delivered by the carrier to the platen, and key operated means to swing said carrier against the platen to deliver an impact blow thereagainst, and geared means responsive to the force of said impact to drive the eraser element into erasing contact with and across the area to be erased.

2. A key operated erasing attachment for a typewriter comprising an arm, key operated means to impel said arm toward the platen of the typewriter, a plunger slideable on said arm and normally projecting therefrom, erasing means movably carried by said sliding means, a rack carried by said arm and a pinion carried by said plunger and engaging said rack to actuate said erasing means upon a movement of the plunger out of its normally projected position in response to an impact blow against the typewriter platen.

3. A key operated erasing attachment for a typewriter comprising an arm, key operated means to impel said arm toward the platen of the typewriter, means slideable on said arm and normally projecting therefrom, erasing means movably carried by said sliding means, and rack and pinion driving means associated with said arm and said slideable member to actuate said erasing means upon a movement of the slideable means out of its normally projected position in response to impact with the typewriter platen, said slideable means being movable transversely of said arm and comprising a hollow member terminating at its forward end in a pair of spaced guards, said erasing means being movable between said guards for contact with a sheet of paper on said platen.

4. A key operated erasing attachment for a typewriter comprising an arm, key operated means to impel said arm toward the platen of the typewriter, means slideable on said arm and normally projecting therefrom, erasing means movably carried by said sliding means, and means associated with said arm and said slideable member to actuate said erasing means upon a movement of the slideable means out of its normally projected position in response to impact with the typewriter platen, said slideable means being movable transversely of said arm and comprising a hollow member terminating at its forward end in a pair of spaced guards, said erasing means being movable between said guards for contact with a sheet of paper on said platen, said last named means including a rack and pinion drive between said slideable means and said arm.

5. A key operated erasing attachment for a typewriter comprising an arm, key operated means to impel said arm toward the platen of the typewriter, means slideable on said arm and normally projecting therefrom, erasing means movably carried by said sliding means, and means associated with said arm and said slideable member to actuate said erasing means upon a movement of the slideable means out of its normally projected position in response to impact with the typewriter platen, said erasing means comprising a rotatable member, a belt on said rotatable member and driven thereby, and erasing elements carried by said belt.

6. In a key operated erasing attachment for

a typewriter having a platen, an eraser element, a swinging carrier for the eraser element, said eraser element being movable in the carrier in a direction substantially parallel to the axis of the platen in response to an impact blow delivered by the carrier to the platen, key operated means to swing said carrier against the platen to deliver an impact blow thereagainst, said

eraser element comprising a belt, and a series of sharp erasing members carried by said belt, and means on the carrier operable by the force of said impact blow to move the eraser members carried by the belt in erasing contact with a sheet on said platen.

CHARLES R. BENNETT.
